GAME BOARD

Robert Lash Robbins, Jr., Hollywood, Calif., assignor, by mesne assignments, to Milton Bradley Company, a corporation of Massachusetts

Application September 30, 1947, Serial No. 777,044

5 Claims. (Cl. 273—134)

1

An object of my invention is to provide a game in which the element of suspense is maintained throughout the playing of the game. In fact, the player first finishing the game may not be the winner. Only after the values of the respective stock certificates have been tabulated and totaled on a score card, will the winner of the game be determined.

The value of the stock certificates is subject to fluctuation during the playing of the game and this increases the interest of the player. In addition, the game has historical and geographical points of interest which will be of educational value to the players.

Another novel feature of the game is the ability of any player to move his playing piece or counter if his number appears on one of the dice even though another player threw the dice. Since a player can only advance his counter if his number appears on one of the dice regardless of who makes the play, it is possible for him to make a throw of the dice when his turn comes and not be able to move his own counter if the numbers appearing on the dice are not his number. The game can be played in a relatively short time so as not to become tedious to the players.

Other objects and advantages will appear in the following specification, and the novel features of the device will be particularly pointed out in the appended claims.

My invention is illustrated in the accompanying drawings forming a part of this application, in which:

Figure 1 is a plan view of the game on a greatly reduced scale;

Figure 2 is an enlarged view of the globe portion of the game and illustrates the courses to be taken by the various counters;

Figure 3 is a perspective view of several of the stock certificates used in the playing of the game;

Figure 4 is a perspective view of several of the playing counters;

Figure 5 is a perspective view of the playing dice;

Figure 6 is a plan view of the score card; and

Figure 7 is a plan view of the six stock certificates used.

While I have shown only the preferred form of my invention, it should be understood that various changes or modifications may be made within the scope of the appended claims without departing from the spirit and scope of the invention.

In carrying out my invention, I provide a game with a playing surface indicated generally at A

in Figure 1. The game playing surface is square and may be made of any desired material, such as paper, cloth or canvas, and of any size. The game itself is preferably thirty inches times thirty inches in area and is known as the playing board. It is intended for use on a standard size card table.

If the playing area is of the size above noted, the outer portion of the game will consist of a six-inch wide circular band indicated generally at B whose outer circumference 10 is substantially tangent to the four sides 11 of the playing board A. The band is divided into a plurality of equal arcuate segments. In the present game I have illustrated six such segments and these are numbered from 1 to 6, inclusive. The six numbers follow each other consecutively around the circular band B and the arcuate segments they designate are separately colored. The arcuate segment 1 is colored red, segment 2 is colored black, segment 3 is colored yellow, segment 4 is colored purple, segment 5 is colored blue, and segment 6 is colored green. I do not wish to be confined to these particular colors because other colors could be used.

Each of the six arcuate segments is subdivided into four sections reading in a counter-clockwise direction, Escrow, Bank, Foreign exchange and Receivership. These four sections in the arcuate segment 1 are referred to as 1a, 1b, 1c, and 1d, respectively, when reading in a counter-clockwise direction. In like manner the four sections in the arcuate segments 2 to 6, inclusive, are designated with the number of the segment followed by the letter designating the particular section. The six arcuate segments of the circular band constitute the home bases for the six playing counters and at the center of each segment and tangent to the inner periphery 12 of the band B, I provide small circles 13 divided into two halves. In one half of each circle I print the word "Start" and in the other half I print the word "Finish." The counters of the players start from the half marked "Start" of these circles at the beginning of the game and finish at the half marked "Finish" at the end of the game. The first player to negotiate the course, which will be described in detail, and arrive back at his circle 13 with his counter, completes the playing of the game, but is not necessarily the winner. The arrow a indicates the direction of travel of the counters along the circuitous trail 14.

Within the inner periphery 12 is a central circular area C of the playing board that has an outline map of the world. North and South America,

Europe and Asia are shown. Also certain points of geographical and historical interest are indicated and these are Pearl Harbor, Sydney, the Panama Canal Zone, Rome, London, Berlin, Washington, D. C., Nome, Manila, and Tokyo. These points of interest on the map are joined together in the order named by a circuitous trail 14 of circles that are tangent to each other. The trail starts from near the center circle 15 of the central area C and traverses the map area from Australia to Africa and then from Europe to Japan before returning to the center circle. The small circles forming the trail 14 are consecutively numbered from 1 to 6 and then the numbers repeat throughout the length of the trail with the exception of the circles that indicate the ten points of geographic and historical interest from Pearl Harbor to Tokyo, above mentioned. The numbered circles of the trail have the same color as the corresponding numbered arcuate segments 1 to 6, inclusive, of the outer circular band. The circles of the trail numbered 1 are colored red and so on up to the circles numbered 6 which are colored green. These colored and numbered circles of the circuitous trail 14 have a definite bearing on the playing of the game which will be described shortly. The uncolored and unnumbered circles of the trail associated with the ten points of interest on the map are safety zones and the counters of the players landing on any one of these zones at the termination of a play are safe from any attack by the counters of the opposing players. There are one hundred and forty-four circles forming the circuitous trail 14 counting the center circle 15 twice, although I do not wish to be confined to any particular number.

Between each "Start" "Finish" circle 13 and the center circle 15, I provide a straight invulnerability trail 16 of seventeen squares. These trails are colored the same as the color of the arcuate segment 1 through 6, inclusive, from which they extend. Again, I do not wish to be confined to any particular number of squares contained in these straight and radially extending trails 16. Each of these straight trails is for the private travel of the piece or counter having the same color. I therefore call these straight trails, trails of invulnerability and a player's counter while resting on any square in this trail is declared to be invulnerable and cannot be molested by the counters of opposing players. The purpose of these six radially extending trails 16 is to permit the player to accumulate stock certificates in the Bank in a manner hereinafter described and protects the player against possible immediate bankruptcy when subjected to penalties which the player may encounter when proceeding along the circuitous trail 14 with his counter. The center circle 15 has its area divided into six equal parts and each part is associated with and positioned adjacent to the inner end of each straight trail 16 and is given a like color. The counters of the players move directly from the innermost square on their straight trail 16 to the center circle 15 and thence to the first small circle marked 1 and colored red on the circuitous trail 16. The center circle 15 is used twice by each player during the playing of the game, once in the manner just mentioned and second when the counter leaves the end of the trail 14 and returns to the trail 16.

A plurality of stock certificates shown in Figures 3 and 7 are provided for the players. Each player receives fifty stock certificates at the

start of the game of the same color as the color of the arcuate segment from which he plays. I have shown one stock certificate of each of the six groups and these are numbered from 21 to 26, inclusive. The stock certificate 21 is colored red, and certificate 22 is colored black, certificate 23 is colored yellow, and the certificates 24, 25 and 26 are colored purple, blue and green, respectively. A pair of dice indicated at 27 in Figure 5 are used in the playing of the game.

It will be noted from Figure 1 that the sections 1d, 2d, 3d, 4d, 5d and 6d, entitled Receivership, are marked with five pairs of angle lines disposed adjacent to the sides of the sections and these angle lines are numbered consecutively from 1 to 6 with the exception that the number of the arcuate segment in which the section d forms a part, is omitted. For example, section 1d has no pair of angle lines marked 1; section 2d has no pair of angle lines marked 2; and so on up to section 6d which has no pair of angle lines marked 6. The purpose of these lines will appear in the rules of the game and in the description of the play.

There are six playing counters or pieces, one for each player, and these may be of any shape desired. In Figure 4 I show them conical in shape with a cylindrical base and a spherical head. The counters D are preferably colored the same as the segments so that the player occupying arcuate segment 1 would have a counter colored red, and so on up to the player occupying arcuate segment 6 would have a counter colored green. It is possible to stamp the numbers 1 to 6 on the counters in addition to the coloring if desired. The cylindrical base has a diameter preferably slightly smaller than that of the small colored circles forming the circuitous trail 14 so that when a counter comes to rest on any colored circle at the end of its move, the color of the circle can still be seen. The spherical top could have a miniature map of the world stamped thereon to carry out the illusion of world traveling and dealing in stock certificates that are negotiable in all parts of the world.

A score card is indicated at 28 in Figure 6, and its use will appear when the playing of the game is explained. It is best to set forth the rules of the game at this time and these rules will also explain how the game deals with the ramifications of usual monetary transactions and may be played by one up to six persons. Its associations are geographical and historical; interest is developed through the pursuit of speculation, highlighted by educational and entertainment value.

The unusual feature of the game is the element of suspense. The identity of the winning player is not known immediately at the close of the game; only after the values of the respective stock certificates owned by each player at the end of the game have been tabulated and totaled on a score card can the true winner be determined. During the process of play the initial value of each stock certificate is subject to fluctuation, hence the wealthiest player, in total number of points, is the winner.

If the game is played by only one player, greater interest is developed if he will select from three to five additional counters and plays against them, clockwise, as though such counters were employed by opponents. Should two players participate, it is recommended that each select from one to three additional counters; playing them, individually, and in turn, to win over those of

the other player. If three players participate, it is recommended that each select and play two counters. Four players can fill the playing board in like manner.

The game is played progressively. Each player selects a number from 1 to 6 and a stack of fifty stock certificates corresponding in color with the segment displaying the selected number and places these within the section *a* marked Escrow and places his counter (also corresponding in color) within the half of the circle *13* marked "Start." The players have one throw of the dice and take turns in a clockwise direction, beginning with the lowest selected number.

The object of the game

The object of the game is to liquidate the stock certificates in Escrow by transferring as many stock certificates as possible from Escrow *a* to Bank *b*; to accumulate as many of opponent's stock certificates as possible in the player's Bank, Foreign Exchange *c* and Receivership *d*, and to determine the wealth of all the players based upon the following values of stock certificates remaining in:

1. Escrow—par, or one point, each;
2. Bank—double par, or two points, each;
3. Foreign exchange—triple par, or three points; each; and
4. Receivership—quadruple par, or four points each.

Escrow

The quarterly section *a* of each of the six arcuate segments 1 to 6, inclusive, within which the player deposits fifty stock certificates at the start of the game, and from which stock certificates are transferred into the player's Bank or opponent's Receivership after each legal move.

Bank

The quarterly section *b* of each of the six arcuate segments 1 to 6, inclusive, wherein the player's stock certificates are placed after transfer from player's Escrow following a legal move. Only when in the Bank may the stock certificates be considered legal tender, provided the player is not bankrupt or insolvent.

Foreign exchange

The quarterly section *c* of each of the six arcuate segments 1 to 6, inclusive, wherein opponent's stock certificates are placed after transfer from opponent's Bank due to payments imposed by player for rentals or satisfactions for the opponent's counters coming to rest on the small circles in the circuitous trail *14* that have the same color and number as the player's arcuate segment.

Receivership

The quarterly section *d* of each of the six arcuate segments 1 to 6, inclusive, wherein opponent's stock certificates are placed after transfer from opponent's Escrow in lieu of payments which opponent is unable to make from a depleted Bank. The sections *d* have pairs of numbered angles and the opponent's stock certificates are placed at the proper numbered angles corresponding to opponent's number.

Trail of invulnerability

When the player proceeds with his counter *D*, by reason of legal moves, from "Start" to the center circle *15*, along the trail *16* of seventeen squares displaying the player's selected color, the player is declared to be invulnerable. This enables the

player to accumulate stock certificates in his Bank section *b* and protects the player against any possible and immediate bankruptcy when subjected to penalties which the player may encounter when proceeding along the circuitous trail *14*.

When the player advances his counter *D*, by reason of legal moves, following his return from the trail *14* and the center circle *15* to the "Finish" half of the circle *13*, along the straight trail *16* of seventeen squares having the player's selected color, the player is again declared to be invulnerable. This procedure enables the opponent to enjoy a brief respite from the player's impositions and returns the player to a legal move and playing status as at the "Start" of the game.

Circuitous trail

The circuitous trail *14* is formed by the joining of the one hundred and forty-four colored circles, including the one designated as the center circle *15* (twice counted), and the circles labelled Pearl Harbor, Sydney, Canal Zone, Rome, London, Berlin, Washington, Nome, Manila, and Tokyo. Each player may exercise jurisdiction over twenty-two of these circles which display the player's selected color and number. Advancement of the player's counter is determined by his legal moves and the accompanying transfer of stock certificates is governed by the rules pertaining to speculation, rental, dividend, satisfaction, equity, immunity, Berlin, Tokyo, bankruptcy, insolvency and solvency, as applied to both player and opponent.

Legal moves

There are three kinds of legal moves possible when a player throws the dice:

1. When one of the thrown dice shows upon its uppermost face the player's number, the player shall transfer one share of his stock certificates from the player's Escrow to the player's Bank and the player may advance his counter or marker along the combined trails *14* and *16*, beginning with the straight trail *16* of invulnerability, for the number of squares or circles, equal to the sum of the numbers appearing on both dice.

2. At the throw of the dice where the uppermost faces of both dice show numbers which total "seven" or "eleven," the player making the throw may transfer two of his stock certificates from player's Escrow to Bank and player may move his counter or marker for the number of squares or circles equal to the sum of the numbers on both dice.

3. At the throw of a "double" or where the uppermost faces of both dice show, individually, the player's number who is making the throw, three of the player's stock certificates may be transferred from player's Escrow to player's Bank and player may advance his counter for the number of squares or circles equal to the sum of the numbers showing on both dice.

4. When the player who throws the dice fails to turn up his number on either of the dice, he cannot make a move of his counter for that particular throw.

Opponent participation

Whether or not a legal move is executed by a player who throws the dice, the selected number of an opponent may appear on one or both of the dice. In any event, the opponent whose number appears may transfer one stock certificate from his Escrow to his Bank and advance his counter for the number of squares or circles equivalent,

only, to opponent's selected number. In the event that a "double" of opponent's number appears, opponent may move his counter for the number of squares or circles equal to the sum of both numbers on the dice, but may not transfer more than one stock certificate from his Escrow to his Bank. If two different numbers are turned up and represent the numbers of two opponents, both opponents may move their counters in the manner just explained.

Important! All transfers of stock certificates resulting from legal moves must be executed before the counter is advanced and before all other contingent procedures are employed. An opponent participation is exercised or carried out only following the completion of the play by the player throwing the dice and then, in the order of the lower to the higher number. All orders of play are predicated on this arbitrary procedure. All moves are subject to government by the rules of Berlin and Tokyo, hereinafter explained.

Speculation

This is an alternative legal move to which every player is entitled while at the playing board and at player's and opponent's discretion.

When, by reason of a legal move, player considers that a resulting move may be disadvantageous, player may elect to speculate by up-ending both dice equally and reading the numbers on the bottom faces. When executing a "speculation" the player must first transfer one stock certificate from his Bank to the Bank of each opponent whose selected number appears as a result of the up-ending play. If the throw of the dice results in a "double," the player may not "speculate." If the "speculation" is executed by a player or opponent whose counter and playing status is governed by the rules of Berlin or Tokyo, then the number of stock certificates involved in the transfer must be increased to two or three, respectively, as the case may be.

If the player elects to "speculate" after a throw of the dice which does not result in a legal move, then the player must transfer two of his stock certificates from his Bank to the Bank of each opponent whose selected number appears as a result of the upending of the dice. If the resulting "speculation" is executed by a player or opponent whose counter and playing status is governed by the rules of Berlin and Tokyo, then the number of stock certificates involved in the transfer must be increased to four or six, respectively, as the case may be.

If the player does not elect to "speculate" following a throw of the dice which does not result in a legal move, an opponent whose number appears on both dice (double) may elect to "speculate," but must transfer two stock certificates from his Bank to the player's Bank who made the throw. If the resulting "speculation" is executed by a player or opponent whose counter and playing status is governed by the rules of Berlin or Tokyo, then the number of stock certificates involved in the transfer must be increased to four or six, respectively, as the case may be.

If the player does not elect to "speculate" following a throw of the dice which does not result in a legal move, opponents whose selected numbers appear as a result of the play may elect to "speculate" and may do so after each opponent has transferred one stock certificate from his Bank to the player's Bank who made the throw, provided both opponents are in accord with the procedure. If the resulting "speculation" is exe-

10 cuted by the player or opponent whose counter and playing status is governed by the rules of Berlin or Tokyo, then the number of stock certificates for each involved in the transfer must be increased by two or three, respectively, as the case may be.

Rental

When by reason of a legal move, a player's counter occupies the small circle allotted to an opponent on the circuitous trail #4 and marked with the opponent's number, opponent may demand from the player of one stock certificate; such transfer to be made from player's Bank to opponent's Foreign Exchange.

Dividend

When, by reason of a legal move, a player's counter occupies the small circle allotted to himself on the circuitous trail #4, the player may transfer two stock certificates from his Escrow to his Bank.

Satisfaction

When, by reason of a legal move, a player's counter passes opponent's counter on the circuitous trail #4, opponent may demand payment of one stock certificate; such transfer to be made from player's Bank to opponent's Foreign Exchange.

Equity

When, by reason of a legal move, a player's counter occupies the same small circle with opponent's counter on the circuitous trail #4, no penalty is extracted from the player, but the player may be obliged to execute a "rental" or profit from a "dividend."

Immunity

When, by reason of a legal move, a player's counter occupies one of the areas identified as the center circle #5, Pearl Harbor, Sydney, Canal Zone, Rome, London, Berlin, Washington, Nome, Manila or Tokyo, along with the circuitous trail #4, the player is not governed by the rules of "rental," "dividend," "satisfaction," or "equity," but is declared to be "immune."

Berlin

When, by reason of a legal move, a player's marker occupies the small circle on the circuitous trail #4 identified as Berlin, each opponent not governed by the rules of Berlin or Tokyo, must transfer two stock certificates from his Bank to the player's Bank. The opponents who are governed by the rules of Berlin or Tokyo must transfer four or six stock certificates, respectively, from their Bank to the player's Bank. In the event that player's counter passes Berlin without occupying the circle marked Berlin, no transfer of stock certificates need be executed, but thereafter, until player's counter occupies or passes Tokyo, the number of stock certificates normally transferred under the rules of "rental," "speculation," "dividend," "satisfaction," "equity," "bankruptcy," "insolvency" and "solvency" is doubled.

Tokyo

When, by reason of a legal move, a player's counter occupies the small circle on the circuitous trail #4 identified as Tokyo, each opponent not governed by the rules of Berlin or Tokyo, must transfer three stock certificates from his Bank to player's Bank. The opponents governed by the rules of Berlin or Tokyo must transfer six or

nine stock certificates, respectively, from their Bank to the player's Bank. In the event that player's counter passes Tokyo without occupying the circle associated with the name, no transfer of stock certificates need be executed, but, thereafter, until player's counter occupies or passes the center circle 15, the number of stock certificates normally transferred under the rules of "rental," "speculation," "dividend," "satisfaction," "equity," "bankruptcy," "insolvency" and "solvency" is tripled.

Bankruptcy

When, at any time during the process of play a player has depleted his stock certificates in his Bank and is, therefore, unable to meet the obligations imposed on him by "speculation," "rental," "satisfaction," "equity," "Berlin," "Tokyo," "insolvency" and "solvency," the player must satisfy all of these obligations by transferring the required number of his stock certificates from Escrow to his opponent's Receivership. When, by reason of a legal move, the player would normally be entitled to transfer his stock certificates from Escrow to Bank, the player must, instead, transfer his stock certificates from opponent's Receivership to opponent's Foreign Exchange, beginning clockwise, and in an equitable manner, until all of the player's stock certificates in opponent's Receivership have been redeemed. Until the Receivership of each opponent has been liquidated, the player must not return to normal procedure and shall be declared to be a Bankrupt. The opponent receiving stock certificates from a player shall place them in the section "d" so that their upper edges line up with the corresponding lines bearing numbers which are the same as the number of the player.

Insolvency

When, during the period in which a player is Bankrupt, the player has depleted his Escrow, he must exchange with each opponent, if neither is governed by rules of Berlin or Tokyo, two Foreign Exchange stock certificates for one stock certificate in opponent's Foreign Exchange. The stock certificates involved in this exchange must proceed around the playing board, clockwise, and shall be transferred to the Escrow of the player and opponent, respectively. Until the player returns to normal playing status, he shall be declared to be insolvent. The process of exchanges shall occur each time the player becomes insolvent.

Solvency

When, at any time during the process of play, the player has been able to transfer all of his stock certificates from Escrow to Bank, and is not bankrupt, he is declared to be solvent and each opponent, not governed by the rules of Berlin or Tokyo, must transfer one stock certificate from his Bank to player's Escrow. A player may become solvent as many times during the play as circumstances, predicated upon legal moves and "speculations," may permit.

Completion of game

The player whose counter is first to return to the starting point and arrives at, or beyond, the half of the starting circle 13 marked "Finish," terminates the game. The game is ended, but not necessarily won by this player.

Winner of game

All stock certificates are now counted by each

player; the value of each being classified with respect to the section "a," "b," "c" or "d" of the arcuate segment in which they have been accumulated. The total for each classification is tabulated on a regulation score card, such as shown in Figure 6, or one similarly improvised, and the sum of each becomes the final score on the basis of the following values:

Stock certificates remaining in Escrow—par, or 1 point each;

Bank—double par, or 2 points each;

Foreign exchange—triple par, or 3 points each;

Receivership—quadruple par, or 4 points each.

The "wealthiest" player wins the game.

The stock certificates 21 to 26, inclusive, and shown in Figures 3 and 7, are all identical except for their color and the notation appearing directly under the wording "Stock Certificate." Player one has fifty red stock certificates and the notation indicated at 29 on his certificates reads, "For Player No. 1." In like manner, player two has fifty black certificates and these carry the notation, "For Player No. 2." The fifty yellow certificates carry the notation, "For Player No. 3"; the fifty purple certificates have printed thereon, "For Player No. 4"; the fifty blue certificates have the notation, "For Player No. 5," and the fifty green certificates carry the wording, "For Player No. 6."

All of the stock certificates for each player has this additional information and indicated at 30, printed thereon:

Good for

1 Point when in Escrow

2 Points when in Bank

3 Points when in Foreign Exchange

4 Points when in Receivership

The score card 28 used for totaling the scores and determining the winner at the end of each game is shown in detail in Figure 6. The card has six vertical columns 31, one for each player, and opposite the word "Name" at the head of each column can be written the player's name. The next line 32 in each of the six columns refers to the number of each player and the particular color associated with the number. Under the second row or line in each column appears four lines reading in descending consecutive order as follows:

Par

2 Par

3 Par

4 Par

Two smaller width vertical columns 33 for receiving scoring figures are arranged to the right of these last four "Par" lines and a space 34 entitled "Total" is arranged at the bottom of the smaller width columns 33 for the purpose of receiving the total scores of the players at the end of the game.

As already stated, the game is finished by any player who negotiates the entire course in accordance with the rules and returns his counter D to the "Finish" half of his small circle 13. He does not have to throw a number that will land his counter on the circle 13 for finishing the game.

The number may be more than that needed to cause his counter to reach the "Finish" half of his circle 13. The extra numbers are merely treated as excess and are not used. After the game is finished, the winner is determined.

The score card 28 is used to determine the winner. Each player counts the number of stock certificates still remaining in the Escrow section "a"

75 and according to the notation on each stock cer-

tificate, the player receives one point for each of these certificates and the totals are entered by the score keeper opposite the word "Par" and in the proper column. Each player next counts the number of stock certificates in his Bank section "b," and a number equal to twice the number of certificates is entered in the proper columns and opposite the notation "2 Par." Next the stock certificates in the "Foreign Exchange" section "c" are counted by each player and the total multiplied by three and entered opposite the notation "3 Par." It should be noted that the stock certificates state that three points will be given for each certificate when it is in the Foreign Exchange section.

Finally the stock certificate in the "Receivership" sections "d" are counted by each player and the total number after being multiplied by four is entered opposite the notation "4 Par" and in the proper column representing the player. The items are now totaled and the winner of the game is the one receiving the highest number. He is considered to be the wealthiest player at the end of the game.

I claim:

1. A board for playing a game in which dummy transferable certificates are used in conjunction with movable counters, comprising a playing surface having an outer circuitous course divided into a number of major segments allocated to different players, each of which is divided into a number of sections representing predetermined playing operations, playing course lines for the several players' counters extending inwardly from each section to a common point, and another circuitous playing course line for said counters, starting and ending at said common point, divided into a succession of counter moving steps equivalent in number to said major segments.

2. A board for playing a game of predetermined significance in which sets of dummy certificates of different colors are employed in conjunction with sets of movable, differently colored counters for different players, said board comprising a playing surface having an outer course divided into major segments of different colors allocated to different players, each of which is divided into a number of sections representing different predetermined playing operations, radial course lines for said segments leading to a common central point, a circuitous playing course line for the counters starting and ending at the central point and divided into a plurality of spaces arranged in repeating groups according to the number of segments, the succeeding spaces of each group being also colored the same as said segments.

3. A board for playing a game of predetermined significance employing sets of dummy transferable certificates and for the use of different players and a counter for each player comprising a playing surface having an outer circuitous band divided into major segments allocated to a plurality

of players, each segment being divided into a number of sections representing different predetermined playing operations and containing a geographical map within the band, a circuitous playing course to be traversed by the counters starting adjacent the center of the playing surface and passing across prominent geographical points, said course being composed of successive groups of consecutively numbered spaces corresponding to the number of the segments and interspaced spaces bearing nomenclature indicative of the prominent geographical localities traversed, said playing surface having thereon other beginning and ending playing courses for the counters leading from each players' segment to the point of commencement of the circuitous course.

4. A board for playing a game in which sets of dummy stock certificates and counters for different players are employed, comprising a playing surface having an outer marginal band divided into major segments allocated to a plurality of players, each segment being divided into a number of sections entitled Escrow, Bank, Foreign Exchange and Receivership, each segment having a starting and finishing point at the band, lines of play leading therefrom to a common meeting point over which the counters of the respective players may be moved, and another circuitous graduated line of play for said counters starting from and finishing at said common point.

5. A board for playing a game employing sets of dummy stock certificates and a counter for each player comprising a marginal band divided into major segments each segment being divided into separate sections entitled Escrow, Bank, Foreign Exchange and Receivership, the several Receiver sections in their successive order around the board having markings for indicating certificates which may be captured from each opposing player, said board having graduated playing courses for the counters of the respective players leading inwardly from the respective segments to a common point and provided with another graduated playing course for traverse of the several counters beginning and terminating at said common point.
